RANGE HANDLE OR THE LIKE

Vytant P. Aleks, Rockford, Ill., assignor to National Lock Co., Rockford, Ill., a corporation of Delaware

Filed Sept. 11, 1964, Ser. No. 81,677

Term of patent 14 years

(Cl. D81—25)

FIG. 1 is a front elevational view of a range handle or the like, embodying my new design;

FIG. 2 is a side elevational view thereof;

FIG. 3 is a side elevational view thereof but taken from the side opposite that of FIG. 2;

FIG. 4 is a rear elevational view thereof;

FIG. 5 is an end elevational view thereof; and

FIG. 6 is a cross sectional view taken on the line 6—6 of FIG. 2.

I claim:

The ornamental design for a range handle or the like, substantially as shown.
